CLAIM

We claim the ornamental design for a rear body of modular display unit, as shown and described.

DESCRIPTION

FIG. 1 is a front perspective view of a rear body of modular display unit showing our new design according to a first embodiment;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view of a rear body of modular display unit showing our new design according to a second embodiment;

FIG. 9 is a front view thereof;

FIG. 10 is a rear view thereof;

FIG. 11 is a left-side view thereof;

FIG. 12 is a right-side view thereof;

FIG. 13 is a top view thereof;

FIG. 14 is a bottom view thereof;

FIG. 15 is a front perspective view of the rear body of modular display unit according to the first embodiment shown in FIG. 1; and,

FIG. 16 is a front view of the first and second embodiments of the rear body of modular display unit shown combined in a state of use.

The broken lines in the figures showing portions of the rear body of modular display unit form no part of the claimed design.

(Continued)

The broken lines showing a screen portion in FIG. 15 are for environmental purposes only and form no part of the claimed design.
